CLAIM

The ornamental design for a Nativity scene decoration including Santa Claus and Rudolph, as shown and described.

DESCRIPTION

FIG. 1 is a front elevation view of a Nativity scene decoration including Santa Claus and Rudolph showing my new design;

FIG. 2 is a rear elevation view thereof;

FIG. 3 is a right elevation view thereof;

FIG. 4 is a top plan view thereof; and,

FIG. 5 is a bottom plan view thereof.

All sides not shown form no part of the claimed design.
